US0D1081989S

(12) **United States Design Patent** (10) Patent No.: **US D1,081,989 S**
(45) Date of Patent: ** Jul. 1, 2025

(54) **LOW PROFILE STAPLE**(71) Applicant: **MedShape, Inc.**, Atlanta, GA (US)(72) Inventors: **Jeremy Webster Blair**, Atlanta, GA (US); **Courtney Lynne Kline**, Atlanta, GA (US)(73) Assignee: **MEDSHAPE, INC.**, Atlanta, GA (US)(***) Term: **15 Years**(21) Appl. No.: **29/875,052**(22) Filed: **Apr. 28, 2023****Related U.S. Application Data**

(60) Continuation-in-part of application No. 29/845,472, filed on Jul. 7, 2022, now Pat. No. Des. 1,009,269, which is a division of application No. 29/748,166, filed on Aug. 27, 2020, now Pat. No. Des. 957,636, which is a continuation-in-part of application No. 29/659,375, filed on Aug. 8, 2018, now Pat. No. Des. 895,113, and a continuation-in-part of application No. 16/393,489, filed on Apr. 24, 2019, now Pat. No. 11,020,110, which is a continuation of application No. 16/058,638, filed on Aug. 8, 2018, now Pat. No. 10,307,156, application No. 29/875,052 is a continuation of application No. 17/472,956, filed on Sep. 13, 2021, now Pat. No. 11,911,026, which is a continuation of application No. 17/004,789, filed on Aug. 27, 2020, now Pat. No. 11,116,499.

(57) **CLAIM**

The ornamental design for a low profile staple as shown and described.

DESCRIPTION

FIG. 1 is a perspective view of a low profile staple, according to the present disclosure;

FIG. 2 is a perspective view of a low profile staple, according to the present disclosure;

FIG. 3 is a side view of a low profile staple, according to the present disclosure;

FIG. 4 is a side view of a low profile staple, according to the present disclosure;

FIG. 5 is a side view of a low profile staple, according to the present disclosure;

FIG. 6 is a side view of a low profile staple, according to the present disclosure;

FIG. 7 is a top view of a low profile staple, according to the present disclosure; and,

FIG. 8 is a bottom view of a low profile staple, according to the present disclosure.

The evenly spaced broken lines form no part of the claimed design and illustrate portions of the low profile staple. The long and short broken lines form no part of the claimed design and represent the bounds of the claimed design for illustrative purposes only.
